UNITED STATES PATENT OFFICE.

CHARLES J. SCHIEMER, OF MOUNT JOY, PENNSYLVANIA.

CHERRY-SEEDER.

1,318,181.

Specification of Letters Patent.

Patented Oct. 7, 1919.

Application filed January 3, 1918, Serial No. 210,130. Renewed September 4, 1919. Serial No. 321,655.

To all whom it may concern:

Be it known that I, CHARLES J. SCHIEMER, a citizen of the United States of America, and a resident of Mount Joy, county of Lancaster, State of Pennsylvania, have invented 5 certain new and useful Improvements in Cherry-Seeders, of which the following is a full and clear specification.

The object of this invention is to provide 10 a simple and durable construction, the parts of which will be easy to cast and assemble and which will be easy to operate, as more fully hereinafter set forth.

In the drawings—

15 Figure 1 is a side elevation looking at the rear side of the machine;

Fig. 2 is a plan view of the same; and

20 Figs. 3, 4 and 5 are views hereinafter described.

25 The main standard *a* is provided at its lower end with a suitable device *b* for clamping the machine to the edge of a table. At its upper end it has cast integral with it an inclined guide tube *c*. In this guide tube a reciprocating head *d* is mounted, said head being cast integral with the seeding fork *e* of usual construction. This fork reciprocates through a stripper *f* carried by an inwardly-extending arm *g* cast integral with 30 the guide tube. Cast integral with the face of the head *d* is a pair of separated lugs or ears *h*, in which is journaled the upper pivot *i* of a link *j*, this pivot being confined in the lug by means of a removable thole pin *k* passed through the pivot at a point between the lugs *h*.

35 Cast integral with the clamp member *b* is a supplemental standard *l*, curving forwardly and toward the hopper side of the machine. In the upper end of the standard *l* is held a short shaft *m* having attached to its outer end a crank handle *n* and affixed to its inner end a crank arm *o*. The lower end of the link *j* is pivotally connected to the outer end of arm *o* in the same manner that the upper pivot of this link is connected to the sliding head *d*.

40 The hopper *p* is removably fastened to an inwardly-extending shelf *q* cast integral with the main standard, this hopper being provided with a spout extension *r* at its lower end, into which the fruit drops directly after it is removed from the seeding prong by the stripper. The seeding prong is 45 adapted to work through a seeding device 50

s of the usual construction located in the depression *t* formed in the lower end of the hopper.

It will be observed that by my arrangement of an inclined guideway for the sliding head, the fruit when stripped from the seeding prong will drop directly into the discharge spout and thereby avoid the necessity for special ejecting and stripping devices. By employing a supplemental standard spaced away from the main standard and in front thereof and extending this standard toward the hopper and of the machine, it will be seen that I am enabled to employ a peculiarly effective crank and link 60 arrangement for operating the seeding prong and its carrying head. It will be observed that it is important that the operating crank and link shall be located so that the link in its movement shall clear the 65 guide tube and main standard. With this construction, the link exerts a push and pull action on the head in a direction almost directly in the line of inclination of the guide tube, thereby materially avoiding friction 70 and wear and thus rendering the device exceedingly easy to operate.

75 In Figs. 1 and 2, the hopper *p* is shown cast integral with the spout *r* and the fruit pocket at the lower end of the hopper, so that gravity alone is depended upon to feed the cherries from the hopper proper into the feed pocket to a point over the seeding device *s*. In Figs. 3 and 5, I show a hopper 80 which is automatically tilted by the rotation of a crank to insure the feeding of the cherries to the seeding means. In these views, the hopper member is divided into a hopper proper *p'* and a seeding pocket *p''*, 85 these two parts being pivotally connected together by a horizontal pivot *u*, to permit the hopper *p'* to be tilted upwardly at its rear end to insure the discharge of the cherries into the seeding pocket *p''*. The hopper *p'* is held normally in a substantially horizontal, non-feeding position by means of a light coil-spring *v* connecting the forward end of 90 the hopper to the stationary arm *g*. To tilt the rear end of the hopper upwardly automatically by the rotation of the crank, I 95 provide the hopper with a tappet *w* at its outer side, in the path of the link *j*, so that the said link moves upwardly, strikes the under face of the tappet and tilts the hopper (against the action of the spring *v*) far 100 105 110

- enough to insure the deposit of at least one cherry from the hopper into the seeding pocket p^2 . After the link slides off the tappet in the forward movement of the link, the 5 spring v restores the hopper to its normal horizontal position, in which position it is normally held against stop-lug x projecting rearwardly from the stationary seeding pocket p^2 .
- 10 The cherries pass through a hole y in the front wall of the hopper p' , this hole being amply large to permit the passage of the largest cherries singly, but not large enough to permit two cherries to pass at the 15 same time. A groove z is formed in the bottom of the hopper centrally thereof, so as to guide the cherries to the hole y ; and, in order to insure the cherries in every instance dropping into the seeding pocket p^2 ,
- 20 the forward wall of the hopper is provided with a guard flange a' which curves forwardly and downwardly toward the seed pocket. The tappet w is preferably in the form of a headed lag-bolt tapped into a lug 25 b' projecting laterally from the outer wall of the hopper and locked in its adjusted position by means of a winged lock-nut c' .

Having thus described my invention, what I claim is:

- 30 1. In a cherry seeder, the combination with a main standard and means at its lower end for clamping it to a support and having an inclined guide tube at its upper end, a hopper and seeding device attached to the 35 tube on its inner side, a sliding head mounted in the guide tube and carrying a seeding prong, a supplemental standard rising from the aforesaid clamping device, a shaft journaled in the upper end of this supplemental 40 standard and carrying at its outer end a crank handle and at its inner end a crank

arm, and a link pivotally connecting said crank arm to said sliding head.

2. In a cherry seeder, the combination of a main standard having a clamp member at 45 its lower end and an inclined guide tube at its upper end, a sliding head in this tube carrying a seeding prong, means coöperating with the prong to seed cherries and strip them from the prong, a supplemental 50 standard rising from the clamp member and extending laterally to one side, a shaft journaled in the upper end of the supplemental standard and carrying a crank handle at its outer end and a crank arm at its inner end, 55 and a pivotal link connecting said crank arm to said head.

3. In a cherry seeder, the combination with seeding means embodying a crank mechanism for operating the seeding fork, 60 of a hopper normally held in non-feeding position and carrying an adjustable tappet arranged in the path of said crank mechanism, whereby in the seeding operation the crank mechanism will tilt the hopper and 65 feed another cherry to the seeding mechanism.

4. In a cherry seeder, the combination with seeding means embodying a seeding fork and a crank mechanism for operating 70 the seeding fork, of a hopper normally held in non-feeding position and adapted to be tilted into feeding position and carrying a tappet arranged in the path of said crank mechanism whereby in the seeding operation the crank mechanism will strike said tappet and thus tilt the hopper to feed another 75 cherry to the seeding mechanism.

In testimony whereof I hereunto affix my signature.

CHARLES J. SCHIEMER.
